UNITED STATES PATENT OFFICE.

WILLIAM M. SCOTT, OF TREDYFFRIN TOWNSHIP, CHESTER COUNTY, PENNSYLVANIA.

SWITCHING APPARATUS.

Original application filed February 17, 1923, Serial No. 619,586. Divided and this application filed June 5, 1925. Serial No. 35,058.

My invention relates to electrical switch or automatic circuit breaker structure for controlling or protecting electric circuits carrying current for power, lighting or 5 other purposes.

In accordance with my invention switch or automatic circuit breaker mechanism is disposed within a housing detachably connected to or pivoted upon a second housing 10 into which extend the conductors of the circuit to be protected or controlled for effecting electrical communication with the terminals of the switch or circuit breaker mechanism, in combination with means for 15 detachably fastening the housings to each other in operative relation.

Further in accordance with my invention a base, upon which the switch or circuit breaker mechanism is mounted, and through 20 which its terminals or studs extend into the second housing, is pivoted upon or detachably carried by the second housing and held in operative relation thereto by detachable fastening means; and more particularly in accordance with my invention the detachable fastening means holds the two housings in operative relation to each other to thereby hold the base in operative relation to the second housing.

30 Further in accordance with my invention there may be utilized in combination with the fastening means a lock or locking structure for holding it in the housing-fastening position.

35 Further in accordance with my invention the fastening means comprises members detached from each other and carried respectively by the different housings and which coact as toggle links which preferably overtravel to housing-fastening position.

40 My invention resides in features of structure and combination of the character hereinafter described and claimed.

This application is a division from my 45 prior application Serial No. 619,586, filed February 17, 1923.

For an illustration of one of the various forms my invention may take, reference may be had to the accompanying drawing, in 50 which:

Figure 1 is a side elevational view, partly in vertical section, of structure embodying my invention.

Fig. 2 is a side elevational view, on

smaller scale, of apparatus of the character 55 illustrated in Fig. 1, with the front housing and base swung out from the rear or supporting housing.

Referring to the drawing, upon a base 1, of suitable insulating material, is secured 60 the switch or circuit breaker mechanism which, for example, comprises two circuit breakers side by side, as viewed from the front, and one only of which appears in side elevation in the drawing.

65 The two circuit breaker arms form a so-called "double arm" circuit breaker, the two arms or poles of which are independently operable to normal or closed position, both connected in series in the same circuit, with 70 automatic tipping mechanism, in general of the character described in my prior Letters Patent 1,389,996.

75 Each arm or circuit breaker comprises the main terminals 2 and 3, adapted to be connected or bridged by the laminated contact member 4 carried by an arm 5 pivoted at 7 to the bracket 6 secured upon the base 1. Pivoted to the arm 5 at 8 is a toggle link 9 pivoted at 10 to the toggle link 11 80 pivoted at 12 to the bracket 6. Upon the member 9 is carried the pin or roller 14 for actuating the toggle as hereinafter described. The member 9 carries a pin or roller 15 engaged by the hook latch 16 pivoted at 7, 85 and having a tail 17. Pivoted concentrically with the latch 16 is the latch actuator or bar 18 extending in front of both arms of breaker mechanism and adapted to engage and actuate the tails 17 of the latches 16 to 90 release the members 9.

95 In series with the bridging member 4 is the winding or coil 19 of an overload tripping magnet whose armature 20, pivoted at 21, carries the arm 22 adapted to actuate the tail 18a of the latch actuator bar 18 in clockwise direction to effect actuation of the latch 16 to trip the breaker mechanism. Co-acting with the armature 20 may be a start-delaying device 23 of the sucker type.

100 The base 1 is detachably carried by or pivoted to the rear metal box or housing 24 by suitable hinge hook structure 25, or equivalent, secured to the base 1 and engaging housing 24 which is secured to any suitable support by screws 26, whereby the base 1 and the circuit breaker structure carried thereby are supported by the housing 24 and

pivoted upon it or detachably carried thereby.

Through suitable conduits or pipes 27 communicating with the interior of the housing 24 extend the insulated supply circuit conductors 28 and 29, connected, respectively, to the studs 30 which extend through the base 1 and connect to the upper terminals 2 of the circuit breaker arms.

10 One terminal of each of the magnet coils 19 connects with a lower main terminal 3, and the other terminals of the coils 19 connect with the studs 31 which extend through the base 1 into the rear housing 24 and there connect with the consumption circuit conductors 34 and 35 extending through the lower conduit 27.

15 The switch or circuit breaker mechanism carried upon the base 1 is enclosed in the front housing H, as of sheet metal, provided adjacent its upper rear edge with hook hinges 25^a, similar to the aforesaid hook hinges 25 of and for the base 1, by which it is detachably carried on or pivoted to the rear housing 24 independently of the base 1.

20 Adjacent its lower rear edge, there are secured to the bottom of the housing H, upon its interior, lugs 36 having the up-standing flanges 36^a adapted to engage the front face 25 of the base 1 and hold it, when the parts are in their positions indicated in Fig. 1, in operative relation to both the front and rear housings.

25 The housing H may be fastened or locked in the position indicated in Fig. 1 by fastening means whose elements are attached respectively to the front and rear housings.

30 The fastening means may comprise, for example, upon the bottom of the rear housing 24 the lug or ear 37 in which there is pivoted at 37^a the member 38, in the form of a hasp or bail, adapted to engage in the notch 39 in the link 40 pivoted at 41 to the lug 42 secured to the bottom of the housing H. At its free end the link 40 is provided with a hole 44 brought into alignment with a hole in the lug 43 secured upon the bottom of the housing H. Through these, holes when in register, may be inserted the hasp h 50 of a padlock P, which prevents unlocking or unfastening the housing H from the housing 24.

35 The members 38 and 40 co-act with each other as links of a toggle which, in the position indicated in Fig. 1, is overtravelled, thereby holding the housing H locked to the housing 24, and in addition holding the base 1 in the operative position, indicated in Fig. 1, by the lug 36^a carried by the housing H.

40 By removing the padlock, and rotating the link 40 in clockwise direction about its pivot 41, the link 38 will be caused to travel across the pivotal axis 41 from overtravelled to undertravelled position, thereby causing 45 collapse of the toggle, with separation of

the members 38 and 40 from each other, whereby the housing H may be swung upon its hook hinges 25^a to a position such as indicated in Fig. 2, removing the lug 36^a from position in which it engages and restrains the base 1, allowing the base 1 to be swung to a position such as indicated in Fig. 2. When so unfastened the housing H of the base 1 may be detached at their hook hinges 75 from the rear housing 24.

50 Secured upon the inner side of the front wall of the housing H is a bracket 45, in which is pivoted the hollow or tubular shaft 46 having the bore or hole 47. The shaft 46 extends to the exterior of the housing H, and there is there secured to it, as by pin 48, the operating lever or handle 49. Secured upon the shaft 46 within the housing H, but carried thereby on the bracket 45, is the actuating member 50, whose side edges 85 are adapted to engage and depress the pins or rollers 14 on the toggle members 9.

55 With both arms of the mechanism in open circuit position, by rotating the operating lever 49 in one direction the actuating member 50 will engage and depress one of the pins 14, thereby extending the associated toggle and moving the movable contact member 4 to circuit closing position, in which it is latched by engagement of the latch 16 with the roller 15. Corresponding movement of the lever 49 in opposite direction effects a similar closure of the other arm. A suitable spring, not shown, biases the member 50 to mid or neutral position, indicated in Fig. 1.

60 Pivoted to the inner end of the bracket 45 at 45^a (which may be concentric with 10, as shown in Fig. 1, but has no connection thereto) is the tripping lever 51, a spring 52, under tension, normally holding the lever in the position indicated in Fig. 1.

65 Extending through the hole or bore 47 of the shaft 46 is the rod or plunger 53 having at its outer end the head or button 54, to which is applied the hand or thumb of the operator to push the plunger 53 from right towards the left thereby rotating the tripping lever 51 about its pivot in opposition to spring 52, the lower end of the lever 51 engaging and actuating the tripper bar 18, which then actuates the tails 17 of the latches 16 of both arms, tripping both simultaneously. By the construction just described, the actuating mechanism or member 50 is not moved inwardly with the tripping plunger or rod 53, the actuating member 50 being confined against motion longitudinally of its axis of rotation, and therefore confined substantially to a given plane of rotation.

70 What I claim is:

75 1. The combination with a plurality of housings, of a transverse base constituting a dividing wall between them, automatic cir- 130

cuit breaker mechanism secured on said transverse base in one of said housings, connectors extending from said circuit breaker mechanism through said transverse base into the other of said housings, conductors extending into said other of said housings for effecting electrical communication with said connectors, and means for securing said housings to each other comprising co-acting members carried, respectively, by said housings.

2. The combination with a plurality of housings, of a transverse base constituting a dividing wall between them, automatic circuit breaker mechanism secured on said transverse base in one of said housings, connectors extending from said circuit breaker mechanism through said transverse base into the other of said housings, conductors extending into said other of said housings for effecting electrical communication with said connectors, means for securing said housings to each other comprising co-acting members carried, respectively, by said housings, and a lock for holding one of said members in housing-securing position.

3. The combination with a plurality of housings, of a base constituting a dividing wall between them, automatic circuit breaker mechanism secured on said base in one of said housings, connectors extending from said circuit breaker mechanism through said base into the other of said housings, conductors extending into said other of said housings for effecting electrical communication with said connectors, and means comprising co-acting toggle members pivoted, respectively, to said housings and detachably pivoted to each other to effect an overtravelling toggle.

4. The combination with a plurality of housings, of a base constituting a dividing wall between them, automatic circuit breaker mechanism secured on said base in one of said housings, connectors extending from said circuit breaker mechanism through said base into the other of said housings, conductors extending into said other of said housings for effecting electrical communication with said connectors, means comprising co-acting toggle members pivoted, respectively, to said housings and detachably pivoted to each other to effect an overtravelling toggle, and a lock for holding one of said toggle members in overtravelled position.

5. The combination with a plurality of housings, of a base constituting a dividing wall between them, automatic circuit breaker mechanism secured on said base in one of said housings, connectors extending from said circuit breaker mechanism through said base into the other of said housings, conductors extending into said other of said housings for effecting electrical communication with said connectors, means for pivot-

ing said one of said housings upon said other housing, and means for securing said housings to each other comprising co-acting members carried, respectively, by said housings.

6. The combination with a plurality of housings, of a base constituting a dividing wall between them, automatic circuit breaker mechanism secured on said base in one of said housings, connectors extending from said circuit breaker mechanism through said base into the other of said housings, conductors extending into said other of said housings for effecting electrical communication with said connectors, means for pivoting said one of said housings upon said other housing, and means comprising co-acting toggle members pivoted, respectively, to said housings and detachably pivoted to each other to effect an overtravelling toggle.

7. The combination with a plurality of housings, of a base constituting a dividing wall between them, automatic circuit breaker mechanism secured on said base in one of said housings, connectors extending from said circuit breaker mechanism through said base into the other of said housings, conductors extending into said other of said housings for effecting electrical communication with said connectors, means for pivoting said base upon said other housing, and means for securing said housings to each other comprising co-acting members carried, respectively, by said housings.

8. The combination with a plurality of housings, of a base constituting a dividing wall between them, automatic circuit breaker mechanism secured on said base in one of said housings, connectors extending from said circuit breaker mechanism through said base into the other of said housings, conductors extending into said other of said housings for effecting electrical communication with said connectors, means for pivoting said base upon said other housing, means for securing said housings to each other comprising co-acting members carried, respectively, by said housings, and a lock for holding one of said members in housing-securing position.

9. The combination with a plurality of housings, of a base constituting a dividing wall between them, automatic circuit breaker mechanism secured on said base in one of said housings, connectors extending from said circuit breaker mechanism through said base into the other of said housings, conductors extending into said other of said housings for effecting electrical communication with said connectors, means for pivoting said base upon said other housing, and means comprising co-acting toggle members pivoted, respectively, to said housings and detachably pivoted to each other to effect an overtravelling position.

10. The combination with a plurality of housings, of a base constituting a dividing wall between them, automatic circuit breaker mechanism secured on said base in one of said housings, connectors extending from said circuit breaker mechanism through said base into the other of said housings, conductors extending into said other of said housings for effecting electrical communication with said connectors, means for pivoting said one of said housings upon said other of said housings, means for pivoting said base upon said other of said housings independently of said one of said housings, and means for securing said housings to each other comprising co-acting members carried, respectively, by said housings. 75
11. The combination with a plurality of housings, of a base between them, circuit breaker mechanism secured on said base in one of said housings, connectors extending from said circuit breaker mechanism through said base into the other of said housings, conductors extending into said other of said housings for effecting electrical communication with said connectors, means for pivoting said one of said housings upon said other of said housings, means for pivoting said base upon said other of said housings independently of said one of said housings, and means comprising co-acting toggle members pivoted, respectively, to said housings and detachably pivoted to each other to effect an overtravelling position. 95
12. The combination with a plurality of housings, of a base between them, circuit breaker mechanism secured on said base in one of said housings, connectors extending from said circuit breaker mechanism through said base into the other of said housings, conductors extending into said other of said housings for effecting electrical communication with said connectors, means for pivoting said one of said housings upon said other of said housings, means for pivoting said base upon said other of said housings independently of said one of said housings, means comprising co-acting toggle members pivoted, respectively, to said housings and detachably pivoted to each other to effect an overtravelling position, and a lock for holding one of said toggle members in overtravelled position. 105
13. The combination with a plurality of housings, of a base between them, circuit breaker mechanism secured on said base in one of said housings, connectors extending from said circuit breaker mechanism through said base into the other of said housings, conductors extending into said other of said housings for effecting electrical communication with said connectors, means for pivoting said one of said housings upon said other of said housings, means for pivoting said base upon said other of said housings independently of said one of said housings, a member on said one of said housings engaging said base when said base and said one of said housings are in operative position with respect to each other for holding said base in operative position with respect to the other of said housings, and means for securing said housings to each other comprising co-acting members carried, respectively, by said housings. 115
14. The combination with a plurality of housings, of a base between them, circuit breaker mechanism secured on said base in one of said housings, connectors extending from said circuit breaker mechanism through said base into the other of said housings, conductors extending into said other of said housings for effecting electrical communication with said connectors, means for pivoting said one of said housings upon said other of said housings, means for pivoting said base upon said other of said housings independently of said one of said housings, a member on said one of said housings engaging said base when said base and said one of said housings are in operative position with respect to each other for holding said base in operative position with respect to the other of said housings, and means comprising co-acting toggle members pivoted, respectively, to said housings and detachably pivoted to each other to effect an overtravelling toggle. 125
15. The combination with a plurality of housings, of a base carried by one of said housings and constituting a dividing wall between them, circuit breaker mechanism secured on said base in another of said housings, connectors extending from said circuit breaker mechanism through said base into said one of said housings, conductors extending into said one of said housings for effecting electrical communication with said connectors, means for pivoting said other of said housings with respect to said base, a member carried by said other of said housings and detachably abutting against said base, and means for securing said other of said housings in position in which said member abuts against said base comprising co-acting members carried, respectively, by said housings and detachably engaging each other. 135
16. The combination with a plurality of housings, of a base carried by one of said housings and constituting a dividing wall between them, circuit breaker mechanism secured on said base in another of said housings, connectors extending from said circuit breaker mechanism through said base into said one of said housings, conductors extending into said one of said housings for effecting electrical communication with said connectors, means for pivoting said other of said housings upon said one of said housings. 140

ings, a member carried by said other of said housings and detachably abutting against said base, and means for securing said other of said housings in position in which said member abuts against said base comprising co-acting members carried, respectively, by said housings and detachably engaging each other.

17. The combination with a plurality of 10 housings, of a base between them, circuit breaker mechanism secured on said base in one of said housings, connectors extending from said circuit breaker mechanism through said base into the other of said housings, 15 conductors extending into said other of said housings for effecting electrical communication with said connectors, means for pivoting said one of said housings with respect to said base, a member carried by said 20 one of said housings and abutting against said base to hold it in operative position, a member carried by said one of said housings in detached relation to said circuit breaker mechanism and operable from the 25 exterior of said one of said housings for resetting said circuit breaker mechanism, and means comprising toggle members pivoted, respectively, to said housings and de-

tachably pivoted to each other to effect an overtravelling toggle. 30

18. The combination with a plurality of housings, of a base between them, circuit breaker mechanism secured on said base in one of said housings, connectors extending from said circuit breaker mechanism through 35 said base into the other of said housings, conductors extending into said other of said housings for effecting electrical communication with said connectors, means for pivoting said one of said housings with respect 40 to said base, a member carried by said one of said housings and abutting against said base to hold it in operative position, a member carried by said one of said housings in detached relation to said circuit breaker 45 mechanism and operable from the exterior of said one of said housings for resetting said circuit breaker mechanism, and means for holding said resetting member in operative relation to said circuit breaker mechanism and for holding said base in operative relation to said second housing comprising co-acting members carried, respectively, by said housings. 50

WILLIAM M. SCOTT.
